UNITED STATES PATENT OFFICE

JOSEPH GROSS AND ISAAC HELLMAN, OF BRONX, NEW YORK

DENTAL HANDPIECE

Application filed April 24, 1928. Serial No. 272,492.

This invention relates to dentists' drills, and more particularly to the hand-pieces in which the drills are mounted and by which the drills are manipulated.

The general object of the present invention is the provision of a hand-piece so constructed that it will cause two burrs to operate simultaneously parallel to each other, and further to provide a hand-piece so formed that the burrs may be spread apart in any desired spaced relation to each other within the range of the instrument, this construction enabling the two burrs to be gradually separated while in operation so that the walls of the cavity can be made parallel and beveled at the same time.

A further object of the invention is to provide a structure of this character embodying a split hand-piece, each section of which carries a burr in its driving mechanism, the handle of the hand-piece having means whereby the driving mechanism of the two burrs may in turn be driven, the two sections of the hand-piece being manually shiftable while the burrs are in use to spread them apart or to draw them toward each other.

Other objects will appear in the course of the following description.

Our invention is illustrated in the accompanying drawings, wherein:—

Figure 1 is a top plan view of a dental hand-piece constructed in accordance with our invention;

Figure 2 is a section on the line 2—2 of Figure 1 but on an enlarged scale, the forward end of one of the sections being broken away;

Figure 3 is a section on the line 3—3 of Figure 2;

Figure 4 is a section on the line 4—4 of Figure 3;

Figure 5 is a section on the line 5—5 of Figure 3;

Referring to these drawings, it will be seen that we have illustrated a dentist's hand-piece, as it is termed, which is formed in two shanks A and B, these shanks being substantially alike. Therefore, the description of one shank applies to the other. Each of these shanks comprises a tubular section 10

which at its rear end is formed to provide a portion U-shaped in cross section and designated 11 in Figure 5, these portions forming in effect ears on one section, the extremity of which overlaps the extremities of the ears 55 on the adjacent shanks, and the sections being pivoted to each other by the pins 12. The portions 11 thus provide pivotal connections for the shanks A and B whereby these shanks may be shifted into or out of a parallel position. The forward end of each section 10 is reduced in diameter and screw-threaded, as at 13, for the reception of a second section 14. Extending longitudinally through each section 10 is a shaft 15 which carries 65 at its rear end a pinion 16.

The rear end of the casing or shank 10 is formed with a bearing 17 for the shaft 15. As shown in Figure 2, the section 14 is angularly bent and a shaft 18 which extends longitudinally through this section 14 is angularly disposed with reference to the shaft 15.

For the purpose of connecting these shafts, toothed clutch members 19 are provided on the adjacent ends of the shaft sections 15 and 18 which mesh with each other at their lower portions so that the shaft 18 is driven from the shaft 15. The forward end of the section 14 is reduced in diameter and screw-threaded, and fitting over this reduced end is a terminal section 20 angular in form, wherein is disposed a drill-carrying shaft 21 extending at right angles to the shaft 18. This drill-carrying shank carries upon it the beveled gear wheel 22 adapted to engage with a beveled gear wheel 23 mounted upon the shaft 18. A drill shank 24 is adapted to be inserted in the drill-carrying member 23 to be rotated thereby. This is the usual dental drill. The drill is held in place within the chuck or member 23 by the pivoted latch 25, such as usually found on dental hand-pieces.

It will be seen that so far we have described a dental hand-piece which, except for the pivoted rear end, is identical with the ordinary dental hand-piece, the ordinary dental hand-piece having the shaft 15 extending out from the rear end of the section 10 and being adapted to be connected to a flexible power-driven shaft. It will be seen that our inven-

tion comprises a double dental hand-piece, the two shanks or halves being pivotally connected to each other so that they may be shifted into a parallel or divergent or convergent relation.

A shaft 26 common to both of the shafts 15 is provided whereby these shafts may be driven. To this end, the shaft 26 which is supported in a bearing handle 27 carries upon it a gear wheel 28 which is large relative to the pinion 16. The pivotal center 12 of the two halves of this double dental hand-piece is coincident with a diametrical line extending through the axis of the gear wheel 28, and hence in order to permit the proper swinging movement of the two halves or shanks, the pinions 16 are transversely concave, the concavity having a curvature such that the center of this curvature is coincident with the pivotal axis 12 so that in all positions of the parts power will be transmitted from the wheel 28 to the pinions 16.

For the purpose of manually shifting these two shanks into or out of divergent relation, we mount upon the shaft 26 the slide 29. This slide has a plurality of apertured lugs through which the shaft passes and the slide is provided upon its under face with the finger piece 30 whereby it may be manipulated. The slide at its forward end is pivotally connected to two links 31 which extend divergently outward and in turn are pivotally connected at 32 to the forward ends of the sections 10 in any suitable manner, these sections 10 being recessed to receive these links and permit their operation.

In the operation of this device, power is transmitted to shaft 26 from any suitable source of power by means of a flexible shaft or other like instrumentality and both the shafts formed of the sections 15 and 18 are rotated at a high rate of speed, thus driving the drills 24 at a high rate of speed.

It will be seen that this hand-piece holds two dental burrs parallel to each other which work simultaneously in two opposite directions on a tooth. The two burrs may be held in parallel relation, of course, while they operate or they can be adjusted while in operation to any desired distance from each other within the range of the instrument, which is ordinarily one inch. The two burrs while they operate may also be gradually shifted apart or gradually brought together so as to form bevels or dove-tails.

The purpose of the hand piece is to facilitate the preparation of parallel walls in a tooth for inlays or similar restorations where parallelism of the walls is essential. It can also be used for the preparation of parallel beveled walls for inlays or making parallel grooves on two opposite sides of a tooth for three-quarter crowns or Carmichael crowns, and the device can be used in any instance where it is desired that the burrs shall move

in parallelism to each other or should be accurately diverged or converged. The device can also be used in preparation of the grooves for a pin ledge attachment. Obviously, the casings or outer enclosures of the shafts will be provided with means whereby the interior parts may be oiled.

Obviously, minor details may be changed without departing from the spirit of the invention as defined in the appended claims.

We claim:

1. A dental hand-piece of the character described comprising two shanks, the shanks being pivotally connected to each other for movement into or out of divergent relation, driven shafts disposed in each shank, each shank at its end having a burr engaging the driven shaft thereof, means common to both shafts whereby both shafts may be driven simultaneously and manually operable means whereby the shanks may be shifted toward or from each other.

2. A dental hand-piece of the character described comprising two shanks pivotally connected to each other for movement into or out of divergent relation, a driving shaft supported between the two shanks and having means whereby it may be connected to a driving means, lateral shafts, one for each of the shanks, extending longitudinally therethrough and having a pinion, the driving shaft having a gear engaging the pinion, each shank at its extremity having a burr engaged by the longitudinal shaft of the shank and extending at right angles to the shaft but geared thereto, and manually operable means whereby the shanks may be shifted toward or from each other.

3. A dental hand-piece of the character described comprising two members, each having a longitudinally extending driving shaft and a rotatable burr carrier at the end of the member operatively connected to said shaft, the two members being pivotally connected to each other for movement into or out of divergent relation, a driving shaft disposed between the two members and operatively connected to the shafts thereof to drive the two lateral shafts simultaneously, and manually operable means for shifting the shafts into or out of divergent relation comprising a slide mounted upon the driving shaft and having a link connection to the two members, the slide having a thumb piece whereby it may be shifted.

4. A dental hand-piece of the character described comprising two members, each member having a casing, the members being pivotally connected to each other for movement into or out of divergent relation, a driving shaft supported between the two members and having means whereby it may be connected to a driving means, a lateral shaft supported by each of said members, the driving shaft having a gear and the lateral shafts

each having a gear meshing with the first named gear, each member at its end having a burr-engaging shaft extending at right angles to the shaft of the member but geared thereto, and manually operable means whereby the members may be shifted toward and away from each other.

5. A dental hand-piece of the character described, comprising two shanks, the shanks being pivotally connected to each other for movement into or out of divergent relation, driven shafts extending longitudinally through each shank, each shank at its end having a burr engaging the driven shaft thereof, means common to both shafts whereby both shafts may be driven simultaneously, a longitudinally shiftable, manually controllable member disposed between said shanks, and links pivotally connected to the longitudinally shiftable member and to the shanks whereby the shanks may be shifted into or out of divergent relation.

6. A dental hand-piece comprising two shanks being pivotally mounted for movement into or out of divergent relation, driven shafts disposed in each shank, means common to both shafts whereby both shafts may be driven simultaneously, and manually operable means to shift the shanks toward or from each other.

In testimony whereof we hereunto affix our signatures.

JOSEPH GROSS.
ISAAC HELLMAN.
